CONSTRUCTIONAL MATERIAL

Filed Dec. 12. 1925

Inventor:
Albert C. Fischer,

By Ballard *[Signature]*

UNITED STATES PATENT OFFICE

ALBERT C. FISCHER, OF CHICAGO, ILLINOIS, ASSIGNOR TO THE PHILIP CAREY MANUFACTURING COMPANY, A CORPORATION OF OHIO

CONSTRUCTIONAL MATERIAL

Application filed December 12, 1925. Serial No. 75,152.

This invention relates to expansion joints surfaced with a rubber film in order to make same waterproof and air tight, acting as a packaging sealing means, preserving the body 5 of the joint and preventing adhesion to other strips when crated. By expansion joints are meant premoulded expansion strips, as known to the art.

Absorption tests are made by highway officials in order to judge the value of expansion joints, and inasmuch as light and air affect bituminous materials it is a desirable feature to coat the expansion joint surface with a material which will prevent access of air or 15 light to the bituminous material.

The preformed expansion joints may be made up in any suitable way, as is known to the art, and they are usually prepared in strips $\frac{1}{4}$ inch to 2 inches in thickness, and in 20 any length up to 12 or 15 feet, and in width equal to the depth of the pavement or structure in which they are to be used.

In order to better describe my invention, I have illustrated, in the accompanying drawings, a form of pre-molded expansion embodying my invention.

Referring to the drawings:

The single figure shows a cross section taken through a strip of material embodying my 30 invention.

The expansion joint of my invention comprises a core, a , which may be formed of a suitable fibrous material and which may, if desired, be impregnated with bituminous material. The core is enclosed with a sheath, b , of rubber, which may be applied to the core in any convenient manner, as by spraying or dipping the core into a solution of rubber or uncoagulated latex and thereafter allowing 35 the film of rubber or latex to dry. Thereafter the rubber film may be vulcanized or not as desired. This process results in the formation of a rubber sheath partially entering and interlocking at its inner surface with the outer surface of the core to form a secure con-

nnection between the core and the sheath whereby the latter may not easily be detached from the core.

In preventing ingress of light and air into the outside pores of the expansion joint the 50 life of the material will be preserved.

Likewise expansion joints are formed out of fibrous materials matted, and my purpose would be to surface saturate or coat such fibrous matted sheets with the same rubber 55 coating material which consists primarily of uncoagulated latex. This material is furnished in uncoagulated state and contains about two (2) per cent ammonia, thirty-three (33) per cent rubber and approximately six- 60 ty-five (65) per cent water. The sheets may be immersed in this uncoagulated latex and this mixture, or the mixture may be applied to the surface of the sheets by spraying. This can be accomplished with any suitable rig- 65 ging for paint sprayers, which are known to the market. The moisture will evaporate, leaving a rubber film upon the surface and filling the pores of the fibrous matted mate- 70 rial, or the expansion joint, as described.

It is readily understood that where the fibrous material is not saturated with bituminous material the statement relative to air and light would not apply, but it would make the 75 fibrous matted material waterproof.

Uncoagulated latex, as described, can readily be purchased on the market, and is shipped in this state.

Likewise the surface of the core, a , may first be treated with a film of sulphur dust, 80 should it be desirable to vulcanize the rubber surface film or sheath b , the sulphur dust is a vulcanizing agent and may, if desired, be mixed directly with latex before the latter is sprayed or otherwise applied to the core, and any other suitable vulcanizing agent 85 may be used, which would impart some of its properties to the latex when placed upon the surface, and by heating the same a vul- 90 canized film of rubber will be produced.

However, it is not essential that the film be vulcanized, as it is a very thin film.

Another object of my invention is to prepare an expansion joint with a bituminous material, the sides of which are produced without dusting material or interfering surfaces, and placing directly over this bituminous surface of the expansion joint a film of uncoagulated latex, thus closing all the pores and shutting out the light and air.

Expansion joints are often prepared in a heated state, and where this is done the evaporation of course, will be faster than where this does not occur.

15 The latex film will be particularly advantageous in preventing adhesion of the strips in shutting out the air and light, and in closing the pores, thus making the absorption properties of the joint practically zero.

20 Fibrous matted materials may be procured on the market in various shapes and forms, and insulating materials which are matted may be employed for this purpose when utilized for expansion joints, but it has always 25 been found more practical to utilize bituminous mixtures with fibrous matter, because of the better resistance to strains and pressures.

30 The material produced by this treatment is waterproof, light and air proof and the surface may be coated with a dusting material if preferred, in which case the dusting material would either be applied first to the surface of the strips and then coated with latex, 35 or the material would be coated with latex first and then have dusting material placed thereover. This would not be necessary in the case of fibrous matted material utilized for the purpose of expansion joints. This 40 fibrous matted material may be a dried vegetable fibre, matted substance compressed, or any one of the numerous insulation materials which are found on the market, which will subject themselves to this treatment.

45 As it is not new to manufacture premoulded expansion joints, I am leaving to the art, as disclosed in the United States Patent Office over a long period of years, the various structures, as I believe there is invention and 50 utility in a light, air and moisture proof film coating of latex.

I claim:

1. An expansion joint comprising a pre-formed compressible strip having the sides thereof surfaced with rubber.

2. An expansion joint comprising a pre-formed strip of waterproof fibrous material having the sides thereof surfaced with rubber.

60 3. An expansion joint comprising a pre-formed strip of matted waterproof fibrous material having the sides thereof surfaced with rubber.

4. An expansion joint comprising a pre-

formed compressible body having the outer sides thereof surfaced with rubber.

5. An expansion joint comprising a pre-formed core of matted fibrous material having an outer sheath of rubber.

6. Constructional material comprising a preformed compressible core of bituminous composition and a rubber sheath for sealing said core.

Signed at Chicago, Illinois, this 13th day of October, A. D. 1925.

ALBERT C. FISCHER.
